UNITED STATES PATENT OFFICE.

JOHN W. SMALL, OF BURLINGTON, NORTH CAROLINA.

THREADING ATTACHMENT FOR SHUTTLES OF LOOMS.

1,353,076.

Specification of Letters Patent. Patented Sept. 14, 1920.

Application filed July 7, 1920. Serial No. 394,460.

To all whom it may concern:

Be it known that I, JOHN W. SMALL, a citizen of the United States, residing at Burlington, in the county of Alamance and 5 State of North Carolina, have invented a new and useful Threading Attachment for Shuttles of Looms, of which the following is a specification.

This invention has reference to threading 10 attachments for shuttles of looms and its object is to provide an easily applied attachment readily adaptable to existing shuttles, whereby the shuttle may be threaded with a minimum of effort and without liability of putting the thread under undue 15 strain in either threading or in the operation of the shuttle.

In accordance with the invention the shuttle may be of customary form with a central 20 cavity to carry the usual bobbin; and one end of the cavity is covered by a plate in turn supported by a post or leg made fast at convenient points to the shuttle, and tension means are provided, around and 25 through which the thread is carried to ultimately leave one side of the shuttle through an eye guiding the thread as the shuttle moves back and forth in its course.

The invention is restricted to the devices 30 or structures by means of which the thread is supported and tensioned in passing from the bobbin to the material being woven.

The invention will be best understood from a consideration of the following detailed 35 description taken in connection with the accompanying drawings forming part of this specification, with the understanding, however, that the invention is not confined to any strict conformity with the showing 40 in the drawings, but may be changed and modified so long as such changes and modifications mark no material departure from the salient features of the invention as expressed in the appended claims.

45 In the drawings—

Figure 1 is a plan view of the shuttle with the improvement applied.

Fig. 2 is a side elevation of the portion of the shuttle shown in Fig. 1.

50 Fig. 3 is a section on the line 3—3 of Fig. 2.

Fig. 4 is a perspective view of the guide and tension plate forming part of the improvement.

Fig. 5 is a section on the line 5—5 of Fig. 4.

Fig. 6 is a detailed view of the eye plate from which the thread emerges.

Referring to the drawings there is shown a shuttle 1 which may follow the usual lines 60 and consequently requires no special description, and the shuttle is shown as provided with a bobbin 2 and thread 3 thereon, as is customary. The shuttle has a longitudinal cavity 4 to receive the bobbin 2. The shuttle is provided with opposite nose ends 5, of which but one is shown, it being understood that the two ends of the shuttle are similar except that at one end tension devices are provided, while these tension devices are omitted from the other end of the shuttle.

Tension devices located at one end of the cavity 4 in the shuttle comprise a plate or table 6, which may be conveniently of metal, 75 and at one end the plate is provided with a post or leg 7 terminating in a foot 7^a shaped to engage the bottom of the cavity 4 and having a slant or trend toward the other end of the shuttle. The foot 7^a is provided with an eye 8 of proper shape to pass a screw 9 and receive the head thereof. Extending from one side of the table 6 is an arm 10 so located and shaped as to lie against the adjacent inner face of one side wall of the shuttle 1, 80 and this arm is secured to the shuttle by a screw 11 or in other appropriate manner.

The leg 7 is located approximately midway of the width of the table and the latter is strengthened by an expanded web 12 90 merging into the leg 7. Through the top of the table 6 are elongated slots 13 and underlying the table beneath the slots is an elastic tension member or finger 14 having spaced ribs 15 partially entering the slots. The finger 14 is made fast to the table at the end toward the leg 7 and between the latter and the arm 10, the arrangement being such that the arm will give toward the end remote from the bobbin to a limited extent.

The face of the bobbin adjacent to the arm 10 is recessed as shown at 16, and in this recess there is seated a tension plate 17 held in place by a screw 18 or in other appropriate manner. The plate 17 is provided with a tongue 19 engaging in a notch 20 in the adjacent edge of the plate 6.

The edges of the plate 6 presented toward

the adjacent margin of the cavity in the bobbin 1 are rounded, these edges being indicated at 21, 22 and 23, the edge 23 merging into a rounded edge 24 on the plate 17 following closely the contour of the recess 16 but not touching the shuttle walls. The edge 24 is also a rounded edge leading to near the bottom end of the plate 17 and there merging into a slit 25 in turn terminating in an eye 26 also with rounded edges, for the eye is designed to permit the passage of the thread coming from the bobbin.

When the shuttle is placed in the loom the thread is properly adjusted by taking the free end of the thread, of which a sufficient quantity is drawn from the bobbin, and this thread is readily passed about the plate 6, first along the edge 21 thereof, then along the edge 22 and finally along the edge 23, which brings the thread under the plate against the web 12 and over the elastic end of the tongue 14. The thread follows the web 12 toward the bobbin over the tongue 14, thence over the ribs 15 to the rear ends thereof which are notched as shown at 27, thus preventing the return movement of the thread. Then the thread is directed along the edge 24 of the plate 17 until the slit 25 is reached, after which the thread will pass easily into the eye 26 and be brought away from the shuttle to the proper part of the loom. The thread passes from the bobbin about the post 7, which latter has a cutaway portion or notch 28 guiding the thread so that it then lies along the web 12 in partial encircling relation to the post 7, thence over the finger 14 and the ribs 15 on the finger through the notches 27, thence back to the plate 17 to and through the eye 26. In this manner the thread, which is applied by practically one movement, is placed under tension and is guided at several points. There is the tension caused by the bobbin which does not rotate but from which the thread may be drawn. Then the portion of the thread about the post 7 adds to the tension of the thread, after which the passage of the thread, in a somewhat tortuous course in front of the ribs 15 and then along the back of the plate 17 and through the eye 26, supplements the tension with the thread guided about curved surfaces preventing undue tension sufficient to injure the thread.

What is claimed is:

1. The combination with a loom shuttle, of a threader therefor comprising a guide plate mounted in the bobbin receptacle at one end of the shuttle, a guide and tension post, for the thread, carrying the plate, a guide and tension bar and finger carried by the plate on the under side thereof and engaged by the thread, and a guide and ten-

sion plate having an eye therein for the passage of the thread from the threader and associated with the first named plate. 65

2. A threading attachment for loom shuttles comprising a guide plate situated in the bobbin compartment of the shuttle in spaced relation to the bobbin, said plate having a guide post and an arm carrying it with the plate spaced from the walls of the bobbin compartment to permit the introduction of the thread from the bobbin beneath the plate, a guide and tension finger carried by the plate on the inner face thereof for directing and tensioning of the thread, and another plate fast to the shuttle adjacent to and at one side of the first named plate and provided with an eye through which the thread passes from the shuttle. 75 80

3. A combination with a loom shuttle, of a threader comprising a guide plate provided with an intermediate post or support upholding the plate, with the edges of the plate spaced from the side walls of the shuttle and said plate being provided with a tension and guide finger on its under face, and a guide and tension plate on one side of the shuttle and provided with an eye through which thread leaving the shuttle passes. 90

4. The combination with a loom shuttle, of a guide plate provided with an intermediate post or support upholding the plate with the edges spaced from the side walls of the shuttle and said plate being provided 95 with an intermediate longitudinal web merging into the post, a guide and tension finger carried by the under face of the plate, and a guide and tension plate on the side of the shuttle and spaced to receive thread coming from the tension finger, the last named plate having an eye through it to pass the thread coming from the guide and tension finger on the under side of the first named plate. 100

5. A threading attachment for loom shuttles comprising a guide plate seated in the shuttle with marginal portions in spaced relations to the walls of the shuttle, said guide plate having a supporting post and a web merging into the under face of the plate and into the post, a guide and tension finger carried by the under face of the plate between the web and one edge of the plate, and another plate at one side of the shuttle with one edge of the second plate spaced from the adjacent wall of the shuttle and provided with an eye for passing thread coming from the finger and having a slot entering the eye for guiding the thread to the eye in the threading operation. 110 115 120

In testimony, that I claim the foregoing as my own, I have hereto affixed my signature.

JOHN W. SMALL.
